US00D527027S

(12) **United States Design Patent** (10) **Patent No.:** **US D527,027 S**
Smith et al. (45) **Date of Patent:** **** Aug. 22, 2006**

(54) **EXCAVATOR TOOL CARRIER**

(75) Inventors: **Jeffrey D. Smith**, Guthrie, OK (US);
Cody L. Sewell, Perry, OK (US);
Michael T. Lumbers, Perry, OK (US)

(73) Assignee: **The Charles Machine Works, Inc.**,
Perry, OK (US)

(**) Term: **14 Years**

(21) Appl. No.: **29/236,557**

(22) Filed: **Aug. 17, 2005**

(51) **LOC (8) Cl.** **12-09**

(52) **U.S. Cl.** **D15/24**

(58) **Field of Classification Search** **D15/22-26,**

(57) **CLAIM**

The ornamental design for an excavator tool carrier, as shown.

DESCRIPTION

FIG. 1 is a front elevational view of an excavator tool carrier showing a first embodiment of our new design;
FIG. 2 is a front top right perspective view thereof;
FIG. 3 is a front top left perspective view thereof;
FIG. 4 is a rear top left perspective view thereof;
FIG. 5 is a rear top right perspective view thereof;
FIG. 6 is a left elevational view thereof;
FIG. 7 is a rear elevational view thereof;
FIG. 8 is a right side elevational view thereof; and,
FIG. 9 is a top view thereof.
